UNITED STATES PATENT OFFICE.

GEORGE W. LEWIS, OF GRINNELL, IOWA, ASSIGNOR TO LOVELL MANUFACTURING COMPANY, OF ERIE, PENNSYLVANIA, A CORPORATION OF PENNSYLVANIA.

WRINGER.

1,327,766.

Specification of Letters Patent. Patented Jan. 13, 1920.

Application filed September 21, 1916. Serial No. 121,379.

To all whom it may concern:

Be it known that I, GEORGE W. LEWIS, a citizen of the United States, residing at Grinnell, in the county of Poweshiek and State of Iowa, have invented new and useful Improvements in Wringers, of which the following is a specification.

This invention relates to wringers and consists in certain improvements in the construction thereof as will be hereinafter fully described and pointed out in the claims.

More particularly the invention relates to safety release devices for relieving the pressure on power rolls.

15 The invention is illustrated in the accompanying drawings as follows:

Figure 1 shows a side elevation of the wringer.

Fig. 2 an end elevation of the wringer.

20 Fig. 3 a central vertical section of a portion of the wringer.

Fig. 4 a section on the line 4—4 in Fig. 1.

1—1 mark the stiles of the wringer frame, 2 the upper roll, 3 the lower roll, 4 cross boards, and 5 movable bearings of the upper roll, these bearings being slidingly mounted in the slots 6 in the stiles.

25 Springs 7 are arranged in the slots and rest on the bearings 5. A washer plate 8 rests on the top of the spring and adjusting or pressure screws 9 operate against the plates 8. The screws 9 extend through a cross bar 10. The cross bar is hinged at its outer ends to a hinge plate 12, the hinge 30 plate having a cross plate 12^a bracing the tops of the stiles and outwardly extending ears 12^b through which the hinge pin 13 extends. The bar 10 extends across the slot 6 and between the ears 12^b so that the pivots 35 of the hinges are somewhat outside of the springs 7.

The cross bar is separated intermediate its ends and has the overlapping portions 11.

40 A catch lever 14 is pivotally mounted by means of a pin 15 on the top part of the lapped portion 11 of the cross bar. This is provided with a catch notch 16 which is adapted to engage a pin 17 on the lower part of the lapped portion 11 of the companion part of the bar. It will be readily seen that when both portions are in the 45 position shown in Fig. 1 and the catch lever

in position on the pin 16 that the pressure of the springs 7 is communicated to the frame through the hinge. When, however, 55 the catch 16 is released, the parts of the bar 10 swing upwardly as shown in dash lines, thus releasing the springs and immediately relieving the pressure on the rolls.

One of the advantages of the structure is 60 that the parts of the bar 10 form levers by means of which the springs 7 may be given some initial compression as the parts of the bar are forced into their normal position as shown in Fig. 1.

65 What I claim as new is:

1. In a wringer, the combination of wringer rolls; a spring exerting pressure on the rolls; a frame in which the rolls are mounted comprising a screw exerting pressure on the spring; a cross bar in which the screw is mounted, said cross bar being pivotally secured at its ends to the frame and composed of parts separable intermediate the ends of the bar to release the 75 springs; and detachable means normally holding the parts against separation.

2. In a wringer, the combination of wringer rolls; a spring at each end exerting pressure on the rolls; a frame in which the 80 rolls are mounted; a cross bar pivotally secured at its ends to the frame and opposed by overlapping parts separable along its overlapping portion; screws in the cross bar exerting pressure on the springs; and adjustable means normally holding the parts of the cross bar against separation.

3. In a wringer, the combination of wringer rolls; a spring exerting pressure on the rolls; a frame in which the rolls are 90 mounted comprising a screw exerting pressure on the spring; a cross bar in which the screw is mounted, said cross bar being engaged by the frame at its ends and composed of overlapping parts separable along 95 its overlapping portion to release the spring, one part engaging the frame at one side of the wringer and the other part engaging the frame at the opposite side of the wringer, and detachable means normally holding the 100 parts against separation.

In testimony whereof I have hereunto set my hand.

GEORGE W. LEWIS.
